METHOD OF OBTAINING ADVANCED AND RETARDED IGNITION

Erich Klaiber, Stuttgart, Germany, assignor to
 Robert Bosch Aktiengesellschaft, Stuttgart,
 Germany

Application April 28, 1934, Serial No. 722,980
 In Germany June 24, 1933

7 Claims. (Cl. 123—148)

This invention relates to methods of and means for obtaining advanced and retarded ignition with a magneto having per rotation at least two periods of flux change capable of providing ignition voltages in the generating winding.

One object is to utilize certain of such periods of flux change for producing advanced ignition and certain other of such periods for producing retarded ignition, whereby, if desired, both advanced and retarded ignition, instead of one alone, may occur at periods of substantially the maximum time rate of change of the magnetic flux in the generating winding of the magneto.

Another object is to provide in such a magneto interrupting mechanism for interrupting the circuit of the generating winding at the utilized periods of flux change, and preferably to provide one interrupting mechanism set for advanced ignition and another interrupting mechanism set for retarded ignition, with means for selectively connecting one of the interrupting mechanisms to the generating winding.

Another object is to provide for each position of advanced and retarded ignition, a range of adjustment of the interrupting mechanism, to thereby further increase the total effective range of timing the magneto.

These and other objects will be apparent from the ensuing description and pointed out in the appended claims, in connection with the accompanying drawing which diagrammatically illustrates one embodiment of the invention in application, as an example, to a magneto giving per rotation four fixed periods of flux change for ignition of a twelve cylinder four-cycle internal combustion engine.

The magneto shown has a stator core *a* with poles *b* and *c* and a generating winding thereon comprising primary *d* and secondary *e*. Also it has a stationary magnet with poles *g* and *h*, and a rotor *i* with flux distributing members *k* and *m* driven at three times crank shaft speed of the engine. The poles *b*, *h*, *c* and *g* are serially arranged on 90° spacing. On the rotor shaft *n* is fixed a cam *o* with two lobes 180° apart, and on the interrupter plate are pivoted two interrupter levers *p* and *q* carrying contacts. These levers, with the stationary contacts for them as shown, and the cam *o*, form two interrupting mechanisms operative every 90°, with the lever *q* in advance of the lever *p* in the direction of rotation indicated. The joint terminal of the primary and secondary windings is connected to the arm *r* of a three-point switch,

the other terminal of the primary winding being grounded on the core *a*, and the other terminal of the secondary being connected to the half-speed rotor of the distributor for the twelve sparkplugs indicated at *t*. The halfspeed of the distributor rotor is with reference to the crankshaft speed of the engine. The arm *r* selectively connects the interrupter mechanisms to the generating winding as shown through the advance and retard terminals of the switch, as shown. The interrupter plate has a manual timing lever *u* for conjoint angular adjustment of the interrupting levers *p* and *q* and their fixed contacts, with respect to the cam *o*.

In the position shown on the drawing, the trailing tips *k'* and *m'* of the flux distributors are starting to leave the trailing tips of the poles *b* and *c* respectively, and the cam *o* is starting to separate the contact of lever *q* from its stationary contact. Starting substantially at this moment, there is reduction of the magnetic flux in the core *a* followed by a building up of the flux in the reverse direction therein. Simultaneously, the circuit of the primary winding *d* which is closed through arm *r*, interrupter lever *q* and the ground, is interrupted by *q* to further increase the time rate change of magnetic flux in the core *a* with the well known results. The resulting ignition voltage generated in the generating winding *d*, *e*, and the occurrence of a spark at the proper one of the sparkplugs *t*, occurs at the instant of advanced ignition for the engine cylinder having that sparkplug. At 180° rotation of shaft *n* from the position shown, another spark will occur at the next sparkplug at the same instant of advanced ignition for the engine cylinder having that sparkplug. At the two intermediate 90° positions, there will be a reversal of the flux from the magnet poles *h* and *g* through the core *a*, and an opening of the interrupter lever *p* by a lobe of the cam *o*, but there will be no spark at a sparkplug since the primary winding *d* remains closed through interrupter lever *q* and switch arm *r*. Thus, with this position of switch arm *r*, there will be two ignition voltages generated per rotation of rotor *i*, occurring 180° apart and both at the instant of advanced ignition for the respective cylinders.

Whenever it is desired, as in starting, to change the instant of ignition in each of the engine cylinders to retard the ignition, the switch arm *r* is closed on the upper terminal so that the interrupter lever *p* is connected to the generating winding and the lever *q* disconnected.

therefrom. The circuit of the primary winding *d* will then be opened at the two intermediate points 90° and 270° from the position of the rotor *i* shown on the drawing, at which points the trailing tips *k'* and *m'* will start to leave the trailing tips of the magnet poles *h* and *g*, instead of the stator core poles *b* and *c* as previously described for advanced ignition. Starting substantially at each of these intermediate points, there is a reduction of the magnetic flux in the core *a* followed by a building up of the flux in the reverse direction, and the circuit of the primary winding *d* is opened at the contacts of interrupter *p*, thereby producing a spark at each of the same sparkplugs as before but at the instant of retarded ignition for the respective engine cylinders. Obviously no ignition current is now produced in the generating winding at the positions corresponding to advanced ignition. Thus, with this position of switch arm *r*, there will be two ignition sparks per rotation of rotor *i*, occurring 180° apart and both at the instant of retarded ignition for the respective cylinders, but their angular positions are midway between the two positions for advanced ignition.

As will now be understood, different periods of flux change are utilized for advanced and retarded ignition, to thereby produce equally effective ignition currents at both advanced and retarded ignition in all cylinders of the engine and also to obtain such currents at widely separated positions amounting in this case to 30° between advanced and retarded positions. For engines having twelve or more cylinders, this method of ignition is particularly effective in comparison with prior magnetos utilizing all sparking positions for both advanced and retarded ignition, because of the greater angular movement of the rotor *i* between sparks obtained in accordance with this invention. For four cycle engines having more than four cylinders, this magneto, which is of the type delivering two ignition sparks per rotation, would be driven at greater than crank shaft speed. A twelve cylinder engine would require a magneto rotation of three times crank shaft speed. The angle between advance and retard as measured on the crank shaft is thus reduced to 30°. Similarly, a sixteen cylinder engine requires a magneto rotation of four times crank shaft speed, and the above angle becomes 22.5°. It will also be apparent that alternative magnetos may be used which deliver a different number of ignition sparks per rotation than the type above described. In such cases the magneto rotor speed of each type would differ, but the angle between advance and retard, as measured on the crank shaft, would in each case be the same as for the type above described.

Obviously, this invention may be utilized with a magneto in which the magnetic flux is not reversed in the generating winding, but is reduced to zero or substantially so and thereafter built up in the same direction. In the appended claims, "flux change" is intended to cover the reduction to substantially zero as well as a reversal of the flux at the instant of ignition, but is not intended to include such change as occurs when the flux is altered comparatively slightly during a period to provide advanced or retarded ignition during the one period.

If desired, the periods of ignition, whether advanced or retarded, may be varied manually by the lever *u*. This further enlarges the angular

separation of the instant of advanced and retarded ignition and/or fills in, partially at least, the angular position between the advanced and retarded positions described. Of course, the effectiveness of the spark produced in these angular positions is altered in the same way as that occurring in prior magnetos having adjustment of the interrupting mechanism. Obviously, a governor may be substituted for the lever *u* or may be applied to the cam *o*.

What is claimed is:

1. The method of obtaining advanced and retarded ignition from a magneto having at least two periods of flux change per rotation, which consists in providing twice as many possible periods of ignition as are required, and selecting alternate ones of said periods for advanced ignition and the intermediate alternate ones of said periods for retarded ignition.

2. The method of obtaining advanced and retarded ignition from a magneto which has at least two periods of flux change per rotation and which has one interrupting mechanism set for operation at certain of said periods and another interrupting mechanism set for operation at other of said periods, which consists in selecting one of the interrupting mechanisms for interrupting the circuit of the generating winding of the magneto for advanced ignition and in selecting the other mechanism for interrupting said circuit for retarded ignition.

3. The method of obtaining advanced and retarded ignition from a magneto which has an even number of periods of flux change per rotation and which has one interrupting mechanism set for operation at alternate ones of said periods and another interrupting mechanism set for operation at the intermediate alternate ones of said periods, which consists in selecting one of the interrupting mechanisms for interrupting the circuit of the generating winding of the magneto for advanced ignition and in selecting the other mechanism for interrupting said circuit for retarded ignition.

4. The method of obtaining advanced and retarded ignition from a magneto which has at least two periods of flux change per rotation and which has one interrupting mechanism set for operation at certain of said periods and another interrupting mechanism set for operation at other of said periods, which consists in selecting one of the interrupting mechanisms for interrupting the circuit of the generating winding of the magneto for advanced ignition and in selecting the other mechanism for interrupting said circuit for retarded ignition and conjointly adjusting both interrupting mechanisms with respect to all said periods.

5. In combination with a magneto having a generating winding and at least two periods of flux change per rotation, interrupting mechanism for interrupting the circuit of said winding at certain of said periods, and another interrupting mechanism for interrupting said circuit at certain other of said periods, of selector means for selecting one of said mechanisms for advanced ignition and the other of said mechanisms for retarded ignition.

6. In combination with a magneto having a generating winding and an even number of periods of flux change per rotation, interrupting mechanism arranged to interrupt the primary circuit of said winding at alternate ones of said periods, and another interrupting mechanism ar-

5 ranged to interrupt said circuit at the intermediate alternate ones of said periods, of selector means for selecting one of said mechanisms for advanced ignition and the other of said mechanisms for retarded ignition.

10 7. In combination with a magneto having a generating winding and an even number of periods of flux change per rotation, interrupting mechanism arranged to interrupt the primary circuit of said winding at alternate ones of said

periods, and another interrupting mechanism arranged to interrupt said circuit at the intermediate alternate ones of said periods, of selector means for selecting one of said mechanisms for advanced ignition and the other of said mechanisms for retarded ignition, and means for conjointly adjusting the instant of operation of the interrupting mechanisms.
